JACOB SCHAUB, OF LOGAN, UTAH, ASSIGNOR, BY MESNE ASSIGNMENTS, TO THE CAXTON PRINTERS, LIMITED, OF CALDWELL, IDAHO, A CORPORATION OF IDAHO.

LOCKING MECHANISM FOR LOOSE-LEAF BINDERS.

1,105,161.

Specification of Letters Patent. Patented July 28, 1914.

Application filed April 28, 1913. Serial No. 763,951.

To all whom it may concern:

Be it known that I, JACOB SCHAUB, a citizen of the United States, residing at Logan, county of Cache, and State of Utah, have invented a certain new and useful Locking Mechanism for Loose-Leaf Binders, of which the following is a specification.

This invention is a lock, the same being more particularly intended for use upon one of the permanent covers of a loose leaf binder for the purpose of retaining in a fixed position the slidable member which fastens a series of posts to said permanent cover.

Although the lock is adapted, by reason of its compact construction, for use on the binder-cover, it is evident that said lock may also be used to good advantage in other relations than the particular one specified.

In a prior Patent No. 921,467 granted May 11, 1909 upon an application filed jointly by myself and J. N. Larsen, there is disclosed a lock for loose leaf binders wherein the mechanism required that a certain

key shall remain in position within the lock when the slide was withdrawn in order to release the parts prior to removal of certain pages from, or the insertion of fresh pages into, the binder. The lock of the present invention is designed to operate under similar conditions, but in another embodiment of the invention, the key may be withdrawn when the device is either locked or unlocked.

The objects of the invention are, first, to attain compactness in construction with a view to enabling the lock to take up the least possible space on the binder cover; second, to employ parts of such form that some of them can be easily stamped or pressed out of sheet metal, whereas other parts are cast metal, thus contributing to economy in manufacture; third, to attain security and efficiency in the operation of the mechanism, and finally to simplify the construction.

It should be stated that the lock is intended to be attached to or form a part of one of two binder-plates, the latter being secured to the permanent covers of the loose leaf binder. This binder-plate is provided with notches which receive the apertured end portions of filing posts or pins, and on the binder-plate is slidably mounted a post-locking member, the latter being provided

with pintles which enter the apertures of the filing posts. With the post-locking slide coöperates the lock, the latter operating to preclude movement of the slide when its pintles are engaged with the posts, but when released by the lock, this slide can be manually shifted for withdrawing the pintles from the filing posts, whereby said posts can be moved to positions where certain pages can be removed or fresh pages added as desired.

The lock embodies a casing provided with a transverse guideway, a transverse key seat, and a plurality of longitudinal channels, combined with a post-locking member positioned for movement in the transverse guideway, and a plurality of key-operated tumblers incased within the longitudinal channels and coöperating with the post-locking member, said tumblers being actuated individually by springs so as to lock the post-actuated member except when the tumblers are repressed by an appropriate key.

A novel feature is the construction of the tumbler struck or pressed up from sheet metal and comprising a flat member provided at one end with ears and at its other end with a continuous flange operating as a housing for the spring, the latter acting to impel the tumbler normally to a position wherein the ears will be out of register with wards of the casing and with wards on the post-locking slide, thus preventing said slide from moving in the transverse guideway until the key acts to repress the tumblers for the ears thereof to register with the wards of the casing, whereupon the slide can be shifted for its pintles to be withdrawn from the filing posts.

The tumblers are of varying lengths and forms so that a great many combinations of tumblers and keys are available in the production of different binders for different customers.

Other features of the invention, and the advantages thereof, will appear in the course of the following detailed description.

In the drawings Figure 1 is a plan view of a binder-plate illustrating the slidable member and pintles in their retracted positions, the key being inserted in the lock. Fig. 2 is an enlarged plan view of the lock with the binder-plate removed, the key be-

ing inserted for repressing the slideable tumblers. Fig. 3 is a cross section on the line 3—3 of Fig. 1, said Fig. 3 being on an enlarged scale. Fig. 4 is a plan view of the lock similar to Fig. 2, but showing the slideable notched member in position for the tumblers to lock said member against movement, certain of the tumblers and their actuating springs being omitted. Fig. 5 is a cross section on the line 5—5 of Fig. 1, showing the lock applied to the binder-plate. Fig. 6 is a detail perspective view of one of the slideable tumblers. Fig. 7 is a detail perspective view of the spring retainer. Fig. 8 is a plan view illustrating another form of the notched slideable member.

A designates a binder-plate adapted to be secured in any suitable way to one of the permanent covers of a loose leaf binder, such as the binder disclosed in the prior patent to which reference has been made. The binder-plate consists of a single thickness of sheet metal of the desired length and width. Said plate is provided with a turned over flange a on one of the longitudinal edges thereof, and in addition to this flange said plate is shown as having a series of transverse notches a^2 , the latter being formed in the turned over flanged edge of the plate. B designates a slideable member, herein shown as a flat plate positioned in contact with one face of binder-plate A. The slideable plate is provided at one of its side edges with a series of lugs b^2 which extend into the guide-way formed by the flanged edge a of the binder-plate. The plate B is slideable lengthwise with respect to binder-plate A, and said slideable plate is provided with a series of pintles a' , the latter being secured in any suitable way to the lugs b^2 of said slideable plate. Obviously, the pintles are attached rigidly to the slideable plate for movement therewith, and in one position of the slideable plate the pintles a' thereon extend across the notches a^2 , whereas in the retracted position of the slideable plate the pintles a' are withdrawn from the notches, as shown in dotted lines in Fig. 1. The slideable plate is operable by hand and for this purpose said slideable plate is provided with a finger-piece b^3 , the latter being slideable in a slot a^3 which extends lengthwise of binder-plate A for a suitable distance. The finger piece b^3 is fastened rigidly to a slotted part of the slideable plate, and this finger-piece is guided within, and accessible through, said slot a^3 of stationary plate A.

The filing posts disclosed in the patent to which reference has been made are provided with apertures in the end portions thereof, and with the pintles and sliding plate in the retracted positions shown by dotted lines in Fig. 1, said apertured end portions of the filing posts are adapted to be inserted into notches a^2 of the binder-plate, after which

the slide B is pushed toward the right by applying pressure to finger-piece b^3 , as a result of which the pintles a' are thrust through apertures in the filing posts, thereby locking said filing posts in rigid relation to the binder plate. The slide can be pushed in a reverse direction in order to withdraw the pintles a' from the filing posts when it is desired to remove any of the pages or leaves from said posts, or to add fresh pages or leaves to the binder, as will be readily understood.

The operating parts of the lock are housed or contained within a casing C, the latter being preferably composed of cast metal. The casing is open at one side thereof, and this open side of the casing is applied to the binder-plate A, as shown in Figs. 3 and 5, whereby the binder-plate operates to close the open side of the casing. The casing is adapted to be secured fixedly in position on the binder-plate by suitable means, such as rivets c . The casing is provided with a series of longitudinal channels e , which channels are separated from each other by longitudinal webs or ribs which are parallel to each other and extend from one portion of the casing to a key-seat or slot provided in the other end portion of the casing. The longitudinal webs or ribs and the side walls of the casing are recessed or cut away as at c' , said recessed portion c' constituting a transverse guideway at one end portion of the casing for the reception of the offset part D of the slide B. The recesses c' are provided in the casing so as to result in lugs c^2 forming the wards of the lock casing, said wards c^2 being in alignment transversely of the lock casing. The slide B is provided intermediate its ends with an offset D, shown more clearly in Figs. 4 and 8, and by dotted lines in Fig. 1. This offset is provided with a longitudinal slot d and with two series of notches d^2 d^2 , the notches d^2 of one series being positioned at one side of the longitudinal slot, whereas the notches d^2 of the other series are at the opposite side of the slot, the notches of the two series opening into the slot. The slide is assembled in such relation to casing C that the offset D works in the recesses c' , the wards c^2 fitting in the longitudinal slot d , whereby the offset part D of the slide is free to move in the recessed guideway of the casing, the wards c^2 of said casing working in the longitudinal slot d of said offset. One of the rivets c by which the lock casing is attached to the binder-plate works in the slot d of said offset in the slide.

The lock embodies a plurality of slideable tumblers, four being shown in the drawings, although the number of tumblers is not material. Said tumblers occupy the longitudinal channels e of casing C, and said tumblers coöperate with the notched offset of

slide B and with the key I, the latter being insertible into the transverse key receiving seat or key hole of the casing and the binder-plate.

5 The tumblers F are preferably composed of sheet metal stamped or pressed to the required form, one of said tumblers being shown in detail in Fig. 6. Each tumbler consists of a longitudinal member, a pair of lugs f, and a substantially continuous flange f'. The longitudinal member, lugs f, and flange f' are in one piece, and the tumbler is channeled or chambered so as to form a casing for an actuating spring E. The lugs 10 f at one end of the tumbler extend upwardly from the respective side edges of the longitudinal member, and these lugs f perform the function of detents in locking slide B from longitudinal movement. The flange f' 15 extends upwardly from the longitudinal member at the opposite end from the detent lugs f, and said flange f' is substantially continuous so as to produce the channel or chamber for the spring E. The series of 20 tumblers operate individually in the channels e of the casing so that the springs E will act to impel the tumblers in one direction. With the key out of position the springs act on the tumblers for moving the 25 latter longitudinally within the channels of the casing and to positions wherein the detent lugs f will enter one or the other of the notches d' or d² in the slotted offset of the 30 slideable plate, whereby the detent lugs f will preclude the slideable plate from movement transversely with respect to the casing. 35 Upon the insertion of key I the notched edge thereof will act upon the rounded ends of the tumblers for the purpose of 40 pressing the tumblers against the tension of the springs E to the position shown in Fig. 2, wherein the detent lugs f of the tumblers are brought into register with the wards c² of the lock casing, whereby the detent lugs 45 and the wards will occupy a central position within the longitudinal slot d of slide B, thus permitting the slide B to be moved by applying pressure to finger-piece b³, as heretofore described.

50 The springs E are substantially housed or incased within the chambers or channels of tumblers F, the springs acting individually on the tumblers for the purpose of impelling them across the transverse key seat provided 55 in casing C at one end portion thereof. It will be observed that one end portion of each tumbler is curved or rounded, and said rounded ends of all the tumblers are pressed by the springs across the key-seat i. The 60 springs are thus positioned in compact relation to the tumblers, and said tumblers and springs are compactly positioned within the casing. The springs are retained in operative positions by, and seated against, a 65 spring retainer G. Said retainer is shown

as consisting of a single plate or strip and a series of studs g, the latter being integral with the plate. In the form of spring retainer shown in Fig. 7 the plate and the studs are in one piece, being stamped or 70 struck up from sheet metal, and the plate being slotted so that the studs can be bent therefrom, but, obviously, other forms of spring retainers may be employed. The coiled springs are slipped over the studs g 75 of the retainer so that the springs will be kept in position by the studs, said springs being seated at one end against the retainer plate. The retainer serves the twofold purpose of affording a seat for the series of 80 springs and for keeping all of the springs in proper relation within the channels of the tumblers. This retainer is fitted in notches g' which are provided in the side walls of 85 the casing, and the retainer is thus positioned for operation in the space between lugs f and flanges f' of the tumblers, whereby the tumblers are free to move relative to the retainer G against which the springs are seated.

90 The casing is provided in one end portion with a series of corrugations i adapted to form a key-seat for the key I. The binder-plate A is provided with a longitudinal depression J into which the key is adapted to 95 be slipped when inserting or removing it from the key seat of the casing. The binder-plate is provided with a corrugated shoulder over the longitudinal recess J, and the corrugations of this shoulder register with the 100 corrugations i so as to form a key slot H through which the key is adapted to be thrust.

105 When the slideable plate B is moved for the pintles a' to engage with the filing posts, and the key I is withdrawn, the springs act on the tumblers to position the detent lugs f within one or the other of notches d' d² of the slide B, thereby locking 110 said slide against movement. For releasing 115 the pintles from the filing posts it is necessary to insert the key I into the key-seat, whereupon the edge portion of the key acts on the tumblers to press them back against the tension of the springs, and thus the detent lugs f of the tumblers are brought into 120 register with the wards c² of the casing, as a result of which the detent lugs will occupy the longitudinal slot d in the offset of the slide. With the key in position the slide 125 can be moved to the left for withdrawing the pintles from the filing posts, thus opening the binder, but in the form shown it is necessary to retain the key within the lock so that the slide can be manually operated 130 either to disengage the pintles from the filing posts, or to engage the pintles with said posts. In Fig. 8, however, I have shown a construction of the manually operable slide wherein the slot d is made wider 135

- at one end, as at d^3 , and with this construction of slide the key can be withdrawn when the slide is moved to a position wherein the pintles are disengaged from the filing posts.
- 5 It is preferable under some circumstances to employ a slide constructed as in Fig. 8 for the purpose described.
- Having thus fully described the invention, what I claim as new, and desire to secure by Letters Patent is:
1. In a locking device, the combination of a casing provided adjacent its respective ends with a key seat and with a series of alined wards, a slidable member provided 15 with a longitudinal slot and with transverse notches opening into said slot, said member being positioned for the wards of the casing to occupy the longitudinal slot, a plurality of tumblers positioned within the casing for 20 movement relative to the key seat and to the wards, said tumblers having detents adapted to register with the wards and to enter the notches of the slidable member, and springs 25 acting individually on the tumblers for moving the same to positions across the key seat.
  2. In a locking device, a casing provided with a key seat and a series of parallel channels extending in directions crosswise of 30 said key seat, in combination with a slidable member provided with a longitudinal slot and with notches opening into said slot, said slidable member being movable across said longitudinal channels, a plurality of tumblers each slidable in one channel of said casing, and movable across the key seat, said tumblers being provided with detents adapted to enter the notches of the slidable member, and springs acting individually on said 35 tumblers for positioning the end portions thereof across the key seat, said tumblers being normally positioned for the detents thereof to enter the notches of said slidable member.
  3. In a locking device, the combination of a casing provided with a key seat, a series of alined wards, and a series of channels intersecting with said key seat and extending across the wards, a slidable member 40 provided with a slot and with notches opening into the slot, said member being positioned for the wards to fit into said slot, a series of tumblers slidable within the channels of the casing and movable across the key seat, said tumblers being provided with detents adapted to register with the wards and to enter the notches of the slidable member, and springs coöperating with said tumblers.
  4. In a locking device, the combination of 45 a casing provided with a key seat, a slotted and notched member slidable within said casing in a path parallel to the direction of the key seat, a plurality of channeled tumblers slidably positioned within the casing 50 for movement relative to the key seat and

the slidable member, each tumbler being provided with a fixed detent positioned to enter the slot or one of the notches of said slidable member, and impelling springs each substantially incased within one of said channeled tumblers, said slidable member being projected beyond the casing and accessible for manual manipulation independently of a key which is insertible into the key seat for actuating the tumblers.

5. In a locking device, the combination of a casing provided with a key seat, a slotted and notched member slidable within the casing in a path parallel to the direction of the key seat, a plurality of channeled tumblers slidable within the casing, and across the path of the key seat and the slidable member, each tumbler being provided with a rounded end presented to a key adapted to be inserted into the key seat, each tumbler being provided, also, with a detent in coöperative relation to the slidable member, and springs substantially incased within the tumblers, said slidable member being projected beyond the casing and accessible for manual manipulation independently of a key which is insertible into the key seat for actuating the tumblers.

6. In a locking device, the combination with a notched slidable member, of slidable tumblers coöperating therewith, each tumbler being flanged to produce a channel for incasing a spring, springs positioned separately within the channels of said tumblers, and means against which the springs are seated to afford a yieldable resistance to the movement of the tumblers under the pressure of an appropriate key.

7. In a locking device, the combination with a casing provided with a key seat, of a notched member slidable in the casing parallel to the direction of the key seat, a plurality of slidable tumblers coöperating with said notched member, a spring retainer separate from the casing and positioned therein so as to be in fixed relation to the tumblers, and springs connected to said retainer and acting individually on the tumblers.

8. In a locking device, the combination of a casing provided with longitudinal channels and transverse notches, a spring retainer positioned in said notches, a plurality of slidable tumblers positioned within said channels, a series of springs connected to said retainer and coöperating with the tumblers, and a notched slidable member positioned for engagement by said tumblers.

9. In a locking device, the combination of a casing provided with longitudinal channels and with wards, a key seat extending within the casing transversely to said channels, a slidable member having an offset portion provided with a slot and with notches, said member being slidable within the cas-

ing parallel to the direction of the key seat, a plurality of tumblers slidably confined in the channels of the casing for movement transversely to the key seat and to the 5 slideable member, said tumblers having detents adapted to enter the notches or the slot of said slideable member, and springs acting individually on the tumblers, said slideable member being exposed beyond the casing and accessible for manual operation independently of the key which is insertible into the seat for actuating the tumblers.

10. In a locking device, the combination of a casing provided with a series of webs 15 arranged to produce a series of channels, said webs being recessed and formed with wards, a slide having a slotted offset positioned in the recesses and receiving in the slot the wards of said casing, said slotted 20 offset having notches opening into it, a plurality of tumblers slideable in the channels, said tumblers provided with detents adapted to register with the wards or to enter the notches of the slide, and springs acting 25 on the tumblers.

11. In a locking device, a slide provided with an offset, a longitudinal slot in said offset, one part of the slot being wider than the other, and notches opening into the narrow 30 part of the slot, combined with a casing provided with a key seat and with a

guideway parallel to the key seat, key operated tumblers having detent lugs positioned to enter the notches of said slide, and springs acting on the tumblers, said slide being movable through the guideway of the casing and in a path parallel to the direction of the key seat, said slide being accessible for manual operation independently of the key adapted to be thrust into the key seat. 35

12. In a locking device, a casing provided with a transverse key seat and with a recess forming a guideway, said casing having longitudinal channels extending between the key seat and the guideway, combined with 40 a slideable notched member movable within the guideway in a path parallel to the direction of the key seat, tumblers slideable in the channels and provided with detents to enter the notches of the slideable member, 45 and springs acting on the tumblers for impelling them toward the key seat, said slide being accessible exteriorly of the casing and movable by hand independently of the key adapted to be thrust into the key seat. 50

In testimony whereof I have signed my name to this specification in the presence of two subscribing witnesses.

JACOB SCHAUB.
